UNITED STATES PATENT OFFICE

ERWIN W. TSCHUDI, OF BALTIMORE, MARYLAND, ASSIGNOR TO THE BLACK & DECKER MANUFACTURING COMPANY, OF TOWSON, MARYLAND, A CORPORATION OF MARYLAND

HAMMER RECTILINEAR RECIPROCACTION

Application filed August 19, 1929. Serial No. 386,816.

The invention relates to a power driven hammer of the type having a rotating driving wheel and a reciprocating hammer piece, which is actuated by the successive blows of a striker on the wheel. The hammer piece delivers the blow to the tool and is returned either by the reaction alone or by the reaction assisted by a spring which is convenient, if not essential, in that it serves to hold the hammer piece in engagement with a stop which positions it in the path of the striker. The present invention relates particularly to such a tool in which the hammer piece reciprocates on a rectilinear path.

In the accompanying drawings I have illustrated a hammer embodying the features of the invention in the preferred form.

In the drawings, Figure 1 is a vertical central section taken on the axis of the hammer piece and bit, the plane of the section being at right angles to the axis of the striker wheel.

Figure 2 is a section on the line 2—2 of Figure 1.

Figure 3 is a section on the line 3—3 of Figure 1 looking downwardly.

Figure 4 is a section on the line 4—4 of Figure 1.

Figure 5 is an elevation of the tool on a reduced scale looking at the same in the opposite direction to that in which Figure 1 is taken.

Figure 6 is a fragmentary section similar to the section, Figure 1, showing the same hammer having a striker wheel provided with two striker members.

Figure 7 is an elevation corresponding to Figure 1 showing the hammer equipped with an electric motor.

Figure 8 is an elevation at right angles to Figure 7.

Referring to the drawings by numerals, each of which is used to indicate the same or similar parts in the different figures, the construction shown comprises a frame or casing 1, containing a striker wheel 2 mounted on a shaft 3, to which it is secured in any suitable manner, as by means of keys 3'. The shaft is mounted in suitable bearings 4 in the frame or casing 1, which bear-

ings may be enclosed in bosses 5 on the inside of the casing and bearing at their ends on the sides of the wheel 2, which they serve to position. The casing in the form shown in Figure 1 includes a handle or grip 35.

In accordance with the preferred construction, one of the bearings 4 and the corresponding boss 5 may be supported on a removable plate or cover 6, forming a removable portion of the casing or frame and providing for the convenient removal and replacement of the wheel 2. The construction also includes a hammer piece 8 mounted to reciprocate or slide on a rectilinear path to which it is confined by a barrel 9 formed in the frame or casing 1 and extending from a point 10 in the vicinity of the wheel and near one end of the horizontal diameter to a point 12 near the end of the boss 11 where the barrel is closed by a plug 14 suitably bored at 15 in alignment with the axis of the barrel 9 to receive the shank 16 of a bit 17 which extends into the path of the hammer piece 8, the bit shank 16 being in alignment with the barrel 9 into which it projects.

The striker wheel 2 is provided with one or more striker projections 18, to engage and actuate the hammer piece 8 which striker projections are flat on the side 19 toward the striker piece 8, said flat surface 19 being preferably radial or nearly radial and in striking position preferably at or nearly at right angles to the axis of the barrel 9, which, in the present instance, is a hole bored in the boss 11 of the casing. This bore is preferably at right angles or substantially at right angles to the horizontal diameter of the striker wheel referring to the upright position of the tool as in Figure 1. This horizontal diameter is in line with the striking surface 19 in the striking position, the exact arrangement and selection of these details not being essential.

To assist in returning the hammer piece 2 to striking position a helical spring 20 is provided, the same being mounted in the barrel 9 and bearing at one end against the hammer piece 8 and at the other end against the plug 14. The coil of the helical spring 20 at the upper end is shown as encircling a

boss 21 at the end of the hammer piece 8. To position the hammer piece 8 at the end of its return stroke in the path of the striker projection 18, a stop 22 is provided which may be of any preferred form. In the form of the invention shown it consists of a lever 24 pivoted intermediately on a stud 25, seated i. e. threaded or otherwise in the boss 11 parallel to the barrel 9. This lever 24 extends 15 at one end into the path of the hammer piece 8 on its return stroke, projecting over the end of the barrel 9, in which position it rests on a ledge 26 at the top end of the barrel 11. The other end of the lever 24 is shown 20 as provided with a downwardly disposed tail 28, which bears on the top 29 of the boss 11. The stud 25 projects well above lever 24 and a coil spring 30 encircles the stud 25, bearing at one end against the bottom side 25 of the head 31 and at the other end against the top of the lever 24, around the hole 32 in the lever through which the stud extends. By virtue of the action of the spring 30 a suitable degree of resiliency is imparted to 30 the stop 22 which permits it to yield sufficiently to prevent objectionable hammering or knocking at the end of the up or reverse stroke.

In the form illustrated in Figures 1, 2, 3, 4 and 5, the striker wheel 2 and particularly the striking projection 18 operates in an arcuate slot 34 formed in the upper end of the boss 11 inside of the casing, it being noted that the slot intersects the barrel 9 at the 25 top, permitting the striker wheel proper to rotate in close relationship to and with the hammer piece 8 in its initial or retracted position, as illustrated in Figure 1. The depth of the slot 34 is further sufficient to 30 accommodate the striking projection 18 which, as already pointed out, projects beyond and outward more or less radially from the peripheral surface of the wheel and into the path of the hammer piece 8, so that at 35 each revolution the energy stored by the wheel is imparted directly to the hammer piece which it engages at each stroke projecting it downwardly to the lower end of the barrel where it delivers a blow upon bit shank 36 16 and rebounds as hereinafter described.

In the form of tool shown in Figures 1, 2, 3, 4 and 5, the striker wheel shaft 4 may be driven by means of a flexible shaft 38 which as shown is connected direct to the striker wheel shaft 3 in any suitable manner as by means of the coupling 39.

In operation, the tool or bit 17 being placed in contact with the work, the striker wheel shaft 3 being rotated in any suitable manner 40 as by means of the flexible shaft 38, the projecting striker member 18 comes in contact once in each revolution with the hammer piece 8 which is normally located in the path of the hammer by the action of the spring 20, being positioned by means of the stop 45

22. After the first blow the hammer piece 8 is returned immediately by the recoil and by the action of the spring 20 to the position in the path of the striker projection indicated by reference character 8 in Figure 1. On each forward stroke of the hammer piece, it comes in contact with the top end of the shank 16 of the tool, delivering sharp blows or impacts which are repeated in rapid succession. In each instance the recoil of the hammer piece is quick enough to return it to the path of the striker member projection 18 prior to the advance of the same on the next stroke.

The energy of the blow delivered to the 80 tool 17 by the hammer piece 8 depends on the speed of rotation of the striker wheel 2 and on the diameter of the said wheel and upon the moment of inertia of the striker wheel about its axis.

In Figure 6 I have shown a hammer of similar construction to that of Figure 1, etc. except that in this instance the striker wheel 40 is provided with two striking projections 41 and 42 whereby the number of strokes or 90 blows is increased or multiplied by 2. The number of projections may be increased to a maximum depending upon the relation of the speed of the hammer piece 8 to the speed and constancy of speed of the wheel 2 or 40. 95

In Figures 6 and 7 I have illustrated a portable power driven electric tool embodying the percussive device already described. This construction may be in any proposed form; as shown, there is a handle or grip member 45, to which is connected a cable 46. The grip member 47 contains switch mechanism not shown operated by a trigger lever 48. The grip member 45 is secured to a motor casing or housing 49 containing an 100 electric motor 50. The motor as shown is cooled by a fan 51 secured to the lower end of the motor shaft 52 and surrounded by perforations 53 in the gear casing 54. This gear casing 54 contains a train of reducing gears 110 55, including a pinion 56, which meshes with a gear 57 secured to the striker wheel shaft 58 on which is mounted the striker wheel 59 secured to the shaft to rotate therewith, or the gear 57 and striker wheel may be secured together. The striker wheel, in turn, cooperates with a hammer piece 8 mounted to reciprocate in a barrel 9 to cooperate with the tool 17, having a shank 16, the hammer piece 8 being supported and returned to its 115 normal or initial position by means of a spring 20 and by the recoil. The hammer piece 8 is located in the path of the striker member 18 on the return stroke of the hammer piece by means of the stop 22 which is similar to the stop described in connection with the machine, Figure 1.

The operation of the electrically driven percussion device is very similar to that previously described except that no rotating 130

shaft communicating with the outside is necessary to the operation of the tool, the tool being thrown into and out of operation instantaneously by the operation of the 5 switch lever or trigger lever 48.

I have thus described specifically and in detail a power driven percussive device embodying the features of my invention in the preferred form in order that the nature and 10 the manner of constructing, using and operating the same may be clearly understood. However, the specific terms herein are used descriptively rather than in a limiting sense, the scope of the invention being defined in 15 the claims.

What I claim as new and desire to secure by Letters Patent is:

1. The combination in a portable power hammer of a continuously rotating striker 20 having a striking member rigidly mounted thereon, a reciprocating ram with guiding means therefor engaged by the ram in sliding relation only, causing the ram to move on a path which is substantially tangential 25 to the path of the striker member, means for supporting a bit in the path of the ram at one end of its stroke, a resiliently mounted stop means located at the upper end of the ram guide for checking the rebound of the 30 ram at the opposite end of its stroke and in the path of the striker member and resilient means for supporting the ram in contact with the stop, the stroke of the ram, as controlled by said guide, being so placed and of sufficient 35 length to carry the ram entirely out of the path of the striker, permitting the striker to pass the ram on each full reciprocation.

2. The combination in a portable power hammer of a continuously rotating striker 40 having a striking member rigidly mounted thereon with a striking surface which is substantially radial, a freely reciprocating ram with guiding means therefor engaged by the ram in sliding relation, causing the ram to 45 move on a path which is mainly outside of and substantially tangential to the path of the striker member, means for supporting a bit in the path of the ram at one end of its stroke, a resiliently mounted stop means 50 located at the upper end of the ram guide for checking the rebound of the ram at the other end of its stroke and near the point of tangency, resilient means tending to support the ram in contact with the stop, the path 55 of the ram as determined by the guide causing it to pass completely out of the path of the striker member immediately after contact therewith whereby the striker member passes the ram on each stroke.

59 Signed by me at Towson, Baltimore County, Maryland, this 15th day of August, 1929.

ERWIN W. TSCHUDI.
